(57) **CLAIM**

The ornamental design for a face plate for a multi-media multi-zone interface, as shown and described.

DESCRIPTION

FIG. 1 is a perspective view of the face plate for a multi-media multi-zone interface showing our new design.

FIG. 2 is a front view of the face plate for a multi-media multi-zone interface of FIG. 1.

FIG. 3 is a bottom view of the face plate for a multi-media multi-zone interface of FIG. 1.

FIG. 4 is a right side view of the face plate for a multi-media multi-zone interface of FIG. 1.

FIG. 5 is a top view of the face plate for a multi-media multi-zone interface of FIG. 1; and,

FIG. 6 is a left side view of the face plate for a multi-media multi-zone interface of FIG. 1.

The broken lines define the bounds of the claimed design and form no part thereof. The remaining elements shown in broken lines are for illustrative purposes only and form no part of the claimed design.
